UNITED STATES PATENT OFFICE.

JOHN R. BYRNE, OF BOSTON, MASSACHUSETTS, ASSIGNOR OF ONE-HALF TO
HARVEY WRIGHT, OF MEDFORD, MASSACHUSETTS.

BUTTON-DIE.

SPECIFICATION forming part of Letters Patent No. 663,860, dated December 18, 1900.

Application filed December 17, 1898. Serial No. 699,551. (No model.)

To all whom it may concern:

Be it known that I, JOHN R. BYRNE, a citizen of the United States, residing at Boston, in the county of Suffolk and State of Massachusetts, have made certain new and useful Improvements in Button-Dies, of which the following is a full, clear, and accurate description, reference being made to the accompanying drawings, in which like characters designate similar parts in the various figures.

The object of my invention is to produce a button-die which will increase the speed of manufacturing buttons, thus lessening the cost of production. To accomplish this object, I mount two plunger-sleeves of a die in the same head-plate and employ an automatic means of turning this head-plate so that the two plunger-sleeves will first perform separate functions by coöperating with their respective formers and then by means of the automatic turning device will exchange positions and perform similar functions, only with the plunger-sleeves reversed—that is, two separate functions are performed by each descent of the head-plate, one starting the button and the other finishing it, and no interchange is required by hand, the automatic turning device accomplishing this function. Thus one operation of the die-press performs twice the usual amount of work.

In the drawings, Figure 1 is an isometric view of my button-die. Fig. 2 is a top view of the base with the forming-tube and post-sleeve mounted thereon, the turning-post being in section. Fig. 3 is a section of the base, through the hole through which the turning-post passes, showing said post. Fig. 4 is a vertical section of my button-die. Fig. 5 is an enlarged section of a button made thereby. Fig. 6 shows the separate parts of said button in section. Fig. 7 is a partial sectional view of my button-die with another attachment. Fig. 8 is an enlarged sectional view of a button made thereby. Fig. 9 shows the separate parts of said other button in section.

Referring to Fig. 1, we have the base 1, in which are mounted the tube 2 and post-sleeve 3. These parts are centrally mounted upon the tube-center 4 and post 5, respectively. They are held in their upper positions by the coiled springs 6 and 7, respectively, so that the tube and post-sleeve may be pressed down-

ward by the plunger-sleeves 16 and 17, respectively, thus permitting the tube-center 4 and post 5 to enter the latter, respectively, in the manner well known in dies. The screws 8 and 9 slide up and down in the slots 8^a and 9^a, respectively, the slots thus limiting the extreme positions of the tube 2 and post-sleeve 3.

The base 1 has a U-shaped cut in either end by which it may be clamped to the bed-plate (as in Fig. 4) of a die-press. Between the tube 2 and post-sleeve 3 is a hole in the base, through which passes the turning-post 12, as shown. On the head-plate 13 are mounted the plunger-shanks 14 and 15, with collars 14^a and 15^a to take the upward thrust on the dies. On the plunger-shanks 14 and 15 are mounted, respectively, the plunger-sleeves 16 and 17, which are held up by the latches 18 and 19, respectively. These latches 18 and 19 are mounted in the head-plate 13 by means of the pivots 20 and 21, respectively, and are actuated by the pressure-springs 22 and 23, respectively. These springs are mounted on the ends of the head-plate 13 by screws 13^a. The turning-post 12 is mounted on the head-plate 13 by a screw-threaded shank 24, (see Fig. 4,) and set-screw 25, as shown. The plunger-shanks 14 and 15 are mounted in the head-plate 13 in the same manner by the set-screws 26 and 27, respectively.

In Fig. 4 is shown the bearing-plate 28, mounted on a punch-holder 34 by means of screws 35 and 36. The bearing-plate and the shank 29 of the head-plate are connected through a ball-bearing, which consists in a circular groove (V-shaped) 30 in the bearing-plate 28, with the balls 31 running therein. The circular hardened-steel washer 32 fits over these balls and is screwed fast to the shank 29 of the head-plate 13 by means of the screw 33. To the bearing-plate 28 is rigidly fastened the punch-holder 34, which fits over the bearing-plate, as shown in Fig. 1. It is held by the screws 35 and 36 and is provided with the screw-threaded shank 37, adapted to be screwed into the slide of a die-press.

The lower end of the turning-post 12 has vertical grooves 38 and 39 on either side, into which project the guiding and sliding rollers 40 and 41, respectively. These rollers are mounted in the hardened-steel bushings 40^a

and 41^a in the base 1 and are held in the grooves by means of the pressure-springs 44 and 45, respectively. These springs are screwed to the base by screws 44^a and 45^a. The vertical 5 grooves 38 and 39 are connected by twisting or spiral grooves 42 and 43. (See Fig. 4.)

The switching-guides 46 and 47, near the union of the vertical and the spiral grooves, are so shaped that in the upward movement 10 of the turning-post 12 the rollers 40 and 41, starting in the upper parts of the vertical grooves, will strike the switching-guides and be switched off into the spiral grooves, thus turning the post 12 through one hundred and 15 eighty degrees. After this operation each roller comes to rest in the vertical groove opposite the one where it started.

In the downward movement of the post 12 the rollers will follow their respective vertical 20 grooves and ride over the switching-guides 46 and 47, respectively, the rollers pressing backwardly against the springs 44 and 45.

In Fig. 4 the die is shown screwed to a bed-plate 48 by means of bolts 49 and 50. The 25 lever 51 is pivoted in the yoke 52 by means of the pivot 53. It has a heel-piece 54, which strikes against the base of the yoke to prevent the lever from dropping out of position. The bolt 55 holds the yoke 52 to the table 56 and bed 48 of the die-press. The rod 57 rests upon the lever 51 and slides up and down through the table 56 and bed 48 and in the hole 58 of the post or tube-center 4 to throw out the finished button. The lever 51 is 30 worked by the knee of the operator or by some mechanical connection with the press or in any other suitable way.

Figs. 5 and 6 show the button made by this die. The outside part 60 is of cloth, covering 40 the cap 61, and the edges of the cap are crimped over the back 62, which has the eyelet 63 already attached. The cloth is pinched between the edges of the cap and back, as shown.

45 In Fig. 7 is shown the attachment which makes the button shown in Figs. 8 and 9. In place of the plunger-sleeve 16 and its shank 14 is fastened the bushing 64, of hardened steel, carrying the loosely-sliding pin 65, with 50 the head 66 to prevent it from dropping out of the bushing. This bushing 64 is held in the hole by the set-screw 26. (Shown in Fig. 1.) Fastened to the lower end 67 of the bushing 64 is the coiled spring 68, its lower end 55 fastened to the piece 69, which slides up and down loosely upon the pin 65.

The button in Figs. 8 and 9 has the cloth cover 70, the cap 71, the back 72, with the hole 73 therein, the inside cloth 74, pressed 60 down through the hole 73, forming the tuft 76, by which the button may be sewed to a garment, and the cardboard disk 75 as a filling. The knee-lever and some other parts are omitted in this figure, being shown in Fig. 4.

65 In operation, referring to Figs. 1 and 6, the operator feeds a cap 61 into the post-sleeve 3, so that it fits over the top of the fixed post 5.

Upon the cap is placed the disk of cloth 60 for the cover of the button. When the plunger-sleeve 17 descends, it is held rigidly in place by the latch 19 and the post-sleeve 3 is pressed downward, so that the cover 60 and cap 61 are forced up into the plunger-sleeve 17, the cover fitting snugly over the cap. As the plunger-sleeve 17 is descending the rollers 40 70 and 41 ride upward over the switching-guides 46 and 47 in the vertical grooves 38 and 39, respectively, and when the plunger-sleeves ascend the rollers 40 and 41 strike the switching-guides 46 and 47 and are switched into 80 the spiral grooves 42 and 43, respectively, thus turning the die to its other position. The post-sleeve 3 and post 5 are fed with another cover 60 and cap 61, and into the tube 2 a back 62 is dropped, with the eyelet 63 85 downward. When the plunger-sleeves 16 and 17 next descend, the first operation is repeated between the post-sleeve 3 and plunger-sleeve 16, while the button first started is finished between plunger-sleeve 17 and tube 90 2. As the plunger-sleeve 17 descends this second time it meets the tube 2 and the bevel edge 77 hits the rounded corner 78 of the latch 19, disengaging it from the plunger-sleeve 17, so that the latter is pushed upward 95 on the plunger-shank 15, causing the cover 60 and cap 61 to descend and rest on the tube 2, with the cloth crimped inwardly by the bevel-surface 79. As the plunger-shank 15 and plunger-sleeve 17, which has been arrested in its upward movement by the head-plate 13, continue to descend the back 62 is pressed into the cap 61 by the post 4, and the edges of the cap 61 are crimped by the bevel 79, so as to fold over the edges of the back 100 and hold it securely in place. The cloth is gripped firmly between the edges during this operation and the button is complete. As the plunger-sleeves are again lifted they switch around to their first position again, and as 110 they descend plunger-sleeve 16 coöperates with tube 2 to finish a second button. In this way each descent of the die completes a button.

The plunger-sleeves are twins, while the 115 lower parts differ, each coöperating with both plunger-sleeves successively, but performing different functions.

In Fig. 7 the die makes a different button. The first operation between plunger-sleeve 120 17 and post-sleeve 3 is the same as that in Fig. 4; but between the tube 2 and the pin 65 the action is different. In the tube 2 is fed a back 72, with the hole 73, and also the inside cloth 79, which forms the tuft 76. As the pin 125 descends under pressure of the bearing-plate 28 the pin 65 presses the cloth 74 through the hole 73, thus forming the tuft 76. While the plunger-sleeve 17 and the pin 65 are ascending, turning around, and descending again 130 the cardboard filling 75 is placed on the cloth 74 and the descending plunger-sleeve 17 completes the button on the tube 2, as before. It takes two operations to finish this button,

however, as nothing is done between post-sleeve 3 and pin 65 during the second operation. To prevent interference here, the bearing-plate 28 contains the hole 81; and the pin 5 65, striking the post 5, is pressed upward into this hole. The conical spring 82, held friction-tight in the hole 81 against the shoulder 83, insures the quick return of the pin 65 to its normal position, so that it will not interfere with the turning of the head-plate.

Thus it appears that my button-die, with its pin attachment, will make two kinds of buttons. The die, with its attachment, forms a piece of machinery having two separate functions, and to secure this result the several parts are so designed as to coöperate harmoniously. The plunger-sleeves, head-plate, and bearing-plate require modifications which would be unnecessary without the pin 15 attachment. This coöperation is a valuable feature of my invention. During the descent of the upper part of the die the bearing-plate 28 strikes the head-plate 13 and the ball-bearing receives no thrust or blow. During its 20 ascent the bearing-plate 28 lifts the head-plate 13 by exerting an upward thrust on the washer 32 through the balls 31, thus lifting the head-plate and allowing the turning-post 12 to turn it freely on the ball-bearings.

30 With suitable forms of sleeves, posts, &c., this die will make a great variety of buttons and greatly diminish the time needed in manufacture.

What I claim as my invention, and desire 35 to secure by Letters Patent, is—

1. In a die, a set of upper die parts, a set of lower stationary die parts coöperating therewith mounted immovably on a base, a turning device associated with said base operating 40 to reverse one of said sets of die parts, vertical and spiral grooves in said turning device, a switching-guide, and rollers coöperating therewith.

2. In combination, a punch-holder, a head-plate, a turning device therefor, plunger sleeves and shanks mounted on said head-plate, a tube, tube-center, post-sleeve, and post coöperating with said plunger sleeves and shanks, a hole in said head-plate, and a 45 spring therein, whereby a pin may be substituted for one of said plunger sleeves and shanks, and coöperate with said tube and center, and upon turning, passing upward into said hole against said spring, thereby escaping interference with said post.

3. In combination, a punch-holder, a head-plate, a turning device therefor, plunger sleeves and shanks mounted on said head-plate, a tube, tube-center, post-sleeve, and 50 post coöperating with said plunger sleeves and shanks, and a hole in said head-plate, whereby a pin may be substituted for one of said plunger sleeves and shanks, and coöperate with said tube and center, and upon 55 turning, passing upward into said hole thereby escaping interference with said post.

4. In combination, a base, a punch-holder, a head-plate, a turning device therefor consisting in a rod with straight and spiral grooves mounted on said head-plate and rollers or 70 studs on said base working in said grooves, plunger sleeves and shanks mounted on said head-plate, a tube, tube-center, post-sleeve and post coöperating with said plunger sleeves and shanks.

75 5. In a die, a base, a set of die parts mounted thereon, an ascending and descending head-plate carrying a complementary set of die parts, and a pivotal rod mounted on said head-plate and passing through a hole in said base, straight and spiral grooves in said rod, spring-pressed rollers or studs journaled in said base and projecting into said grooves, and switching-guides in said grooves, said studs riding over said guides when the rod is 80 traveling in one direction, and being deflected or switched into the spiral grooves by said guides, thus turning said roller when it is 85 traveling in the other direction.

6. In a die, a punch-holder adapted to be 90 attached to the press, a head-plate carrying a bearing washer or plate 32 hung on rolling bearings which in turn are supported on the upper side of a bearing-plate 28 fixed to the punch-holder, and die parts mounted on said 95 head-plate each coöperating with a plurality of stationary die parts, and adapted to be shifted from one to another.

7. In a die, a punch-holder carrying a bearing-plate, a head-plate carrying a bearing-washer between two end-thrust bearings, a 100 rolling bearing on its under side, and a direct plate bearing on its upper side to exert the thrust for die-work, and die parts mounted on said head-plate each coöperating with a 105 plurality of stationary die parts.

8. In a die, a punch-holder carrying a bearing-plate, a head-plate carrying a bearing-washer between two end-thrust bearings, a 110 rolling bearing on its under side and a direct plate, bearing on its upper side to exert the thrust for die-work, and die parts mounted on said head-plate each coöperating with a plurality of stationary die parts, and a turning device for said head-plate and die parts 115 thereon.

9. In a die, a punch-holder carrying a bearing-plate, a head-plate carrying a bearing-washer between two end-thrust bearings, a 120 rolling bearing on one side of said washer, and a direct plate on the other side of said washer to exert the thrust for die operations, and die parts mounted on said head-plate, each coöperating with a plurality of stationary die parts.

125 Signed by me this 12th day of December, 1898.

JOHN R. BYRNE.
